CLAIM

The ornamental design for a charger as shown and described.

DESCRIPTION

FIG. 1 is a top, front and left side perspective view of a charger showing our new design;

FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and left side perspective view showing the charger in an alternate state; and,

FIG. 10 is a top, rear and right-side perspective view showing the charger in a second alternate state.

The broken lines in the drawings illustrate portions of the charger which form no part of the claimed design.
